SURFACE WAVE TRANSMISSION LINE

Andre G. Clavier, Nutley, N. J., and David L. Thomas, Lee, London, England, assignors to International Standard Electric Corporation, New York, N. Y., a corporation of Delaware

Application May 23, 1950, Serial No. 163,581

5 Claims. (Cl. 333—95)

This invention relates to microwave transmission systems and more particularly to a single wire guide line for microwave transmission and means for coupling such lines to other forms of microwave transmitting structures.

In addition to the transmission of microwave energy over radio links, coaxial cables and dielectric waveguides, it has recently been discovered that such high frequency energy covering a very wide band may be transmitted by means of a single wire properly insulated, the transmission of energy being confined closely adjacent the wire in the electric and magnetic fields formed thereabout. While it was known that when a wire had electric energy applied thereto that electric and magnetic fields formed about the wire, it was believed that these fields radiated outwardly without any definite limits or boundary. It has recently been discovered however, that if the conductor is coated with a given thickness of insulation the electromagnetic fields produced by microwave energy are concentrated and substantially confined within a given radius about the conductor, this radius being determined by the size of the conductor, the quality and thickness of the insulating coating. By way of example, an ordinary No. 12 enameled copper wire was found to have for microwave energy in the neighborhood of 5000 mc. an electromagnetic field concentrated within a three to four inch radius about the wire and that microwave energy could be propagated in this field closely adjacent the surface of the wire at a velocity slightly less than the speed of light. This manner of propagation now referred to as "surface wave" transmission presents very small loss and is substantially free from electrical and other disturbances where this confined field is substantially unobstructed.

One of the objects of this invention is to provide another form of single wire guide line for microwave surface transmission.

Another object of the invention is to provide a coupling device for single wire guide lines to effect transfer of microwave energy between the guide line and other microwave transmission structures.

One of the features of the invention comprises a variation in the manner of distributing the insulation along the line. While it is known that an insulation coated conductor functions as a guide line for microwave energy, I accomplish this distribution by disposing along a wire conductor a plurality of beads of insulating material spaced at intervals along the conductor. It is also within the scope of my invention to provide in another form a continuous coating of insulation together with beads in the form of enlarged sections of insulating material spaced at intervals therealong. While it is believed preferable to provide the conductor with a distribution of insulation along the surface thereof similar propagation may be obtained along bare wire which presents a finite resistivity comparable to that of ordinary copper wire. Such wire with a coating of insulation is believed to further concentrate the field closer to the surface of the wire.

Another feature of the invention lies in the coupling arrangement for coupling a guide line to the wall struc-

2

tures of coaxial lines and dielectric waveguides. The end portion of a hollow conductor, which may comprise a part or a continuation of the walls of a dielectric waveguide or the outer conductor of a coaxial line, is decreased in conductance gradually to the terminal end thereof. The purpose of this terminal resistance is to absorb terminal losses rather than permit radiation thereof, and thus provide improved transformer matching. This decrease of conductance may be accomplished by different arrangements, one example being the tapering of the thickness of the end portion of the hollow conductor below the effective "skin" conducting thickness of the conductor for a length thereof at the terminal end, and a second example being the continuation of the hollow conductor in constant thickness but decreasing in the conducting consistency thereof until the conductivity is reduced substantially to zero at the terminal end. A third example may comprise the spraying of the end portion of the hollow conductor both the inside and outside surfaces, with resistance material, the resistance layer being decreased gradually away from the end of the conductor.

The terminating insulating material at the end portion of the hollow conductor, whether or not the conductor has a terminating resistance, is preferably enlarged in quantity and/or quality to constrict the field to a radius equal to or less than the radius of the hollow conductor. This insulating material is decreased in amount from the terminal end thereof for a distance outwardly along the line conductor, and may comprise, for example, a solid body of dielectric material or a plurality of beads or discs of insulating material of selected sizes and spacing to produce the desired variation in dielectric quality. The beads may vary in cross-sectional dimensions or they may vary in length or in both cross-section and length. The terminating insulating material may also be decreased in insulating quality for a distance along the line conductor inwardly of the outer conductor. All of these arrangements operate to confine the electromagnetic field closely adjacent the guide line conductor for transfer of propagated microwave energy with a minimum of wave perturbation along the line and between the line and the walls of microwave transmission structures.

The above-mentioned and other features and objects of this invention and the manner of attaining them will become more apparent and the invention itself will be best understood, by reference to the following description of an embodiment of the invention taken in conjunction with the accompanying drawings, wherein:

Fig. 1 is a longitudinal cross-sectional view of a coupling device for coupling a line conductor to a coaxial line;

Fig. 2 is a cross-sectional view taken along line 2—2 of Fig. 1;

Fig. 3 is a longitudinal sectional view of a modified form of coupling device employing beads of insulating material spaced along the conductor line at the coupled end thereof;

Fig. 3A is an enlarged cross-sectional view of one of the beads shown in Fig. 3;

Fig. 4 is a longitudinal sectional view of another embodiment of the invention showing the distributed insulating material of the line in the form of beads with the line coupled to a dielectric waveguide structure; and

Figs. 5 and 6 show in longitudinal section still other modifications of coupling devices.

In Figs. 1 and 2, a single line conductor 1 is shown of the form comprising a conductor wire bearing a continuous coating of insulation 2 which may be of enamel, polystyrene, polyethylene or other insulating material. The coating 2, however, may be omitted where the conductor has the prerequisite resistivity to concentrate the electromagnetic field within a satisfactory radius about

the conductor. The conductor 1 is extended into a hollow conductor 3 of a coupling device which may comprise the terminal end of a coaxial line 4 of the solid dielectric type, the conductor 1 being connected as a continuation of the center conductor 5 of coaxial line. The hollow conductor 3, of course, may be the wall portion of a dielectric guide, such as indicated in Fig. 4. The insulating coating 2 preferably merges or enters into a body of insulation 6, 7 which is disposed within the end portion of the hollow conductor 3. The body of insulation may be made as a single unit or in two or more parts, such as longitudinal halves, thirds or quarters, and held together by a solvent and/or the encircling end of the hollow conductor 3. In Figs. 1 and 2, for example, the body is shown in halves 6 and 7, grooved to receive the line conductor 1. Where the conductors 1 and 5 are of different size, the connecting portion is preferably tapered. The hollow conductor 3 is provided with a terminal end extension 8 which preferably overlaps the body 6, which is decreased gradually to zero conductance at the terminal end 9 thereof. This extension 8 may be formed by tapering the thickness of the conductor 3 so that the conductance thereof is decreased gradually below the normal "skin" conductance of the conductor until it reaches zero. The section 8 may be formed by spraying conductive material onto the body 6, 7 making the coating thereof gradually thinner until the terminal end 9 comprises spaced particles of conductive material. The portion of the body 6, 7 extending outwardly of the terminal end 9 is tapered gradually down to the size of the coating 2.

In Fig. 3 the insulating coating 2 has disposed thereon a plurality of beads of insulating material spaced at intervals along the line conductor 1, as indicated at 10, 11, 12 and 13. These beads 10, 11, 12 and 13 are shown to vary in diameter, the largest being the bead 10 at the terminal end 9 of the hollow conductor 3. The thickness or length d of these beads preferably are much smaller than the wavelength of the microwave energy. The bead 10 preferably closes the terminal end of the member 3 while the beads 11, 12 and 13 are progressively smaller in diameter, the bead 13 closely approaching the diameter of the coating 2. The coating 2 may be discontinued between the first bead 13 and the final bead 10, and also along the line conductor if desired, but as shown in Fig. 3 it is applied to the conductor throughout this length. The coating 2 which preferably is increased in thickness by an added layer of enamel serves to maintain the beads in position as well as to assist in confining the electromagnetic field closely adjacent the conductor 1. The number of beads 10-13 as well as the spacing thereof, may be varied as desired. The center conductor 5 is supported by beads 14 in the usual manner of coaxial lines.

In Fig. 4 a dielectric guide 15 is shown to include a hollow conductor 16 into which line conductor 1A extends, the latter being anchored for tensioning purposes through a turnbuckle 17 to a support (not shown). The conductor 1A is electrically connected by wire gripping fingers 18 of tubular sleeve 19 secured in end cap 20 on the hollow conductor 16. The sleeve 19 insures proper coaxial positioning of the line conductor. In communication with the hollow conductor 16 is a dielectric guide 21 for transfer of microwave energy to the line conductor 1A which may or may not be bare of insulation opposite the dielectric guide 21, a transition connection 22 being provided for either direct connection to the conductor or in capacity coupling arrangement therewith.

The line conductor 1A as shown is a bare wire provided with distributed insulation in the form of beads 23, the spacing S of which is preferably in the order of 10S per wavelength. At the terminal coupling the beads are of different radial sizes, similarly as indicated in Fig.

3. The largest bead 24 is preferably disposed at the terminal end to close the hollow conductor. To reduce

perturbation of the wave propagation at the coupling another series of beads 25 of decreasing sizes is provided at spaced intervals along the conductor inside the hollow conductor 16. The terminal end portion 26 of the hollow conductor 16 is shown in this embodiment to be of constant thickness as distinguished from the tapered thickness of the end portions 8 in Figs. 1 and 2. The material of section 26, however, is so chosen to vary in conductivity throughout its length until the conductance of the section is substantially zero at the terminal end thereof. This may also be accomplished by spraying resistance material on the inside and/or outside surfaces of the hollow conductor, the resistance coating being thickest at the terminal end.

In Fig. 5 the line conductor 1A is the same as shown in Fig. 4, the distributed insulating material being in the form of beads 23 spaced at intervals therealong. These beads by proper spacing provide the same constricting effect upon the electromagnetic field as the continuous coating 2 of Figs. 1 and 2. As the conductor 1A approaches and extends into the hollow conductor 16 the beads are spaced closer and closer together as indicated at 27 until the shortest spacing occurs at the terminal end of the hollow conductor and therebeyond the usual center conductor spacers 14 are employed to coaxially position the line conductor. This concentration of insulating material at the terminal end effectively constricts the electromagnetic field to a cross-sectional volume corresponding to the cross-section of the interior of the hollow conductor 16.

Referring to Fig. 6, the terminal insulating material is shown in the form of beads 28, 29, 30 and 31, which vary both in diameter and length, and, therefore, also in spacing adjacent the terminal end of the hollow conductor 32. The largest bead 28 which preferably is less in length than the wavelength of the microwave energy, is disposed in the terminal end portion 33. Additional insulating beads 34 which are progressively decreased in length to the length of the usual center conductor spacer beads 35 and are interposed between the terminal bead 28 and the first spaced bead 35.

While the various forms illustrated indicate, particularly in Figs. 3 through 6, a limited number of insulating beads as forming the terminating insulating material for the line conductor, it will be understood that the number, sizes and actual spacing of these beads may vary widely depending on the permissible degree of perturbation of wave propagation. Thus, while I have described above the principles of my invention in connection with specific apparatus, it is to be clearly understood that this description is made only by way of example and not as a limitation to the scope of my invention as set forth in the objects thereof and in the accompanying claims.

What we claim is:

1. In a microwave transmission system, means for coupling energy from a coaxial line, to a line conductor capable of microwave surface propagation by means of an electromagnetic field formed thereabout, said means comprising a hollow conductor extending from the outer conductor of the coaxial line, said line conductor being extended into said hollow conductor, said hollow conductor being decreased gradually in thickness toward the end remote from the coaxial line, whereby the conductance thereof is gradually decreased and insulating material disposed about said line conductor within said hollow conductor to constrict substantially the radial extent of the electromagnetic field as it is propagated from the coaxial line to the line conductor.

2. In a microwave transmission system according to claim 1, wherein said quantity of insulation is decreased gradually in insulating characteristic for a given distance outwardly along said line, after the termination of said hollow conductor.

3. The microwave transmission system according to claim 1, and further comprising insulating material, in-

cluding enlarged portions, surrounding the line conductor beyond the termination of said hollow conductor and spaced at intervals therealong.

4. In a microwave transmission system according to claim 3, wherein the size of said sections varies in cross-sectional dimension.

5. The microwave transmission system according to claim 1, wherein said line conductor comprises a portion extending outside said hollow conductor, a layer of insulation surrounding said portion of line conductor, and 10 sections of insulating material of greater radial dimension than said layer of insulation surrounding said conductor and spaced at intervals therealong.
